United States Patent Office.

ALFRED DUVALL, OF BALTIMORE, MARYLAND.

Letters Patent No. 105,319, dated July 12, 1870.

IMPROVEMENT IN TREATING VITRIOLIZED PHOSPHATES.

The Schedule referred to in these Letters Patent and making part of the same.

I, ALFRED DUVALL, of the city and county of Baltimore, State of Maryland, (now temporarily residing in the city and county of Philadelphia, State of Pennsylvania,) have invented a certain Process for Treating or Depositing Vitriolized Phosphates, manufactured for fertilizing purposes, of which the following is a specification.

The crude phosphate, as taken from the deposit, is finely ground or pulverized, and treated or mixed with a given amount of sulphuric or chamber acid, of a strength of 48° or 50°, corresponding to oil of vitriol of 66°, reduced by water to 50° or 48°.

In general practice, in the process of vitriolizing phosphates, according to the views of different manufacturers, and the character of the phosphates being treated, from twenty to thirty-five per cent. (by weight) of oil of vitriol, diluted to 50°, is added to the phosphate being treated; and at the same time, if desired, is added a given quantity of Peruvian guano, fish, from which the oil has been extracted, or salts of ammonia, to give to the phosphate a suitable per cent. of ammonia.

In common practice, the pulverized phosphates are vitriolized and mixed either by hand or in or through an automatic mixer; the vitriolized phosphates, after being mixed, are deposited and allowed to remain in open bulk until sufficiently dry for the final manipulation.

By my process, I run or deposit the vitriolized mixed phosphate, which is in a semi-liquid state, into a tight room or bin of any convenient shape or size, say of a capacity of from two hundred to five hundred tons, which bin is constructed at a level of from ten to fifteen feet below the point from which the vitriolized mixed phosphate falls from the mixer.

I recommend a series of two or more bins adjoining each other, square in shape, having three of their walls permanent, and strongly built of stone, brick, or pitch-pine, with their fronts fitted with tight movable doors, in sections, which are held tight in position by bars and braces, and sufficiently strong to resist the pressure of the semi-liquid against them, though bins may be constructed singly, of any shape, with all their walls movable.

I either cover the top of the bin with a number of tightly-fitting movable hatches, and place in one angle, or any convenient part of the bin, a flue for the

escape of the gases evolved by the action of the acid on the matter being treated, or leave the top entirely open; but the first plan is recommended as being more convenient.

Operation.

The movable doors of the bin being put up and secured in position, the vitriolized mixed phosphate is run in either by hand or automatically, and, being in a semi-liquid state, fills the bin uniformly; and from the heat generated by the action of the acid on the carbonate of lime in the phosphate, the whole mass is kept in a state of ebullition until the bin is filled, thus producing a more thorough mixing and chemical action, it is believed, than can be produced in any other known or practicable way; moreover, the mass being confined, the heat generated has to pass through it perpendicularly in its escape, thereby causing a rapid evaporation of the water contained in the mixture, and leaving the phosphate so dry that, in from forty to fifty hours, the movable doors may be taken down and the mass broken up and removed for final manipulation.

The advantages of my process over that in common use, are—

First, great economy of room.

Second, a great saving in labor in mixing and depositing, as a bin of from four hundred to five hundred tons capacity can be filled in from eight to ten hours.

Third, and most important, a more thorough mixing and chemical action, whereby a larger per cent. of the phosphate is rendered soluble.

Fourth, a quicker and more thorough evaporation of the water contained in the matter treated, whereby it is sooner made ready for the final manipulation.

Claim.

I claim as my invention—

The process for treating or depositing vitriolized mixed phosphates, substantially as described in the foregoing specification, or any modification thereof involving the same general principles.

ALFRED DUVALL.
